UNITED STATES PATENT OFFICE.

EDWIN W. WEBB, OF CHICAGO, ILLINOIS, ASSIGNEE TO STANDARD CAR TRUCK COMPANY, OF CHICAGO, ILLINOIS, A CORPORATION OF NEW JERSEY.

TRUCK STRUCTURE FOR RAILWAY CARS.

Application filed November 12, 1925. Serial No. 68,546.

This invention relates to a truck structure such as commonly used on railway cars and particularly to a novel structure and arrangement of parts for supporting the ends 5 of the bolsters which move between bolster columns of the side frame.

It is an object of this invention to provide a simple and efficient truck structure comprising a side frame having spaced bolster 10 columns with a bottom connecting portion between which columns the end of the bolster projects, said bolster being carried on rollers on a roller plate or cap spring plate supported on springs which are supported at the 15 lower ends by the connecting portion of the bolster column, the springs being arranged at one level.

It is a further object of the invention to provide such a structure as set forth in the 20 preceding paragraph in which the upper ends of the springs are substantially at one level and a cap spring plate or the plate for the roller seat is of simple flat form extended substantially in one plane between the bolster 25 column.

It is a further object of the invention to provide a novel truck structure comprising a side frame having spaced bolster columns between which the end of the bolster is vertically movable, together with a plate forming the roller seat and vertically movable wear plates disposed between each column and the side of the bolster, which plates have their lower ends extending through openings 30 in the roller bearing plate and provided with portions underlying said plate whereby said wear plates cannot lift relatively to the roller plate when in assembled position.

It is also an object of the invention to provide a novel truck structure comprising a side frame having spaced bolster columns which are of U-shape or channel-shape in horizontal cross section with their open sides disposed toward each other having a bottom 40 connecting portion supporting a plurality of springs, the springs adjacent said bolster columns extending into the channel portions thereof.

These and other objects and advantages of 50 the invention will be fully set forth in the following description made in connection with the accompanying drawings in which like reference characters refer to the same parts throughout the different views, and in 55 which

Fig. 1 is a view in side elevation of a truck showing a portion of the side frame and parts assembled therein with some parts broken away;

Fig. 2 is a horizontal section taken substantially on the line 2—2 of Fig. 1, as indicated by the arrows; 60

Fig. 3 is, for most part, a vertical section taken substantially on the line 3—3 of Fig. 1; 65

Fig. 4 is a horizontal section taken on the line 4—4 of Fig. 1;

Fig. 5 is a view in side elevation of the wear plate used; and

Fig. 6 is a view in edge elevation of said plate, as seen from the left of Fig. 5. 70

Referring to the drawings, a truck structure is shown comprising a side frame having spaced bolster columns 7 joined together at their lower ends by a connecting portion 7^a and at their top ends by connecting portions 7^b. The top member 7^b is provided with a central groove or channel through which extends the compression member 8 in the form of a bar rectangular in cross section. The bar 8 is connected to the member 7^b by a plurality of headed and nutted short bolts 13. The bottom portion 7^a of the bolster column has a convex lower surface and lower corner portions with central grooves 75

therein and a tension member or arch bar 9 of hammock shape contacts the bottom of the portion 7^a and extends through the grooves in the said corner portions. The portion 7^a has a downwardly extending central projection 7^c projecting into a central recess 9^a in the bar 9 to assist in holding the 85 parts in proper position. The said corner portions have lugs 7^d at the sides adapted to receive headed bolts 11 which project downwardly in a diagonal direction at each side 90 of the member 9 and pass through holes in a connecting plate 10 clamped against the member 9 by the nuts 11. The member 10 is connected to one end of a bar 12 which 95 extends outwardly to the bottom of the journal boxes, (not shown). The bolster columns 7 are of U-shape or channel shape in horizontal cross section and have their open sides facing each other. At the upper portions 100 of the columns, bearing or wearing surfaces 7^d are provided. These wearing surfaces, as clearly shown in Fig. 2, are formed by a rectangular-shaped web projecting from the inner side of the channel of the column 7, the column at the wearing surfaces thus 105

110

being of box section. The bottom portion 7^a of the bolster column has an annular lug or ring 7^e projecting upwardly therefrom substantially at its central portion which is 5 embraced by an opening in a channel member 14 which extends between the side frames and over the portion 7^a and is held in place by lugs 7^e. A plate 15 is supported on the bottom of channel member 14 also having an 10 opening at its central portion surrounding the lug 7^e and this plate 15 has projections at each end extending beyond the sides of channel member 14, and into the channel-shaped column 7, as shown in Figs. 1 and 4. 15 The shape of this plate is clearly shown in Fig. 4 and it will be seen that said end projections are somewhat curved at their outer ends with a straight outer edge. The 20 sides of the channel member 14 are cut-away at their ends to accommodate the plate 15. The plate 15 forms the bearing plate for a plurality of bolster supporting springs 16. While different numbers of these springs might be used, in the embodiment of the 25 invention illustrated, there are six springs for each side frame. Four of these springs are arranged in a square formation at the central part of the side frame, these four springs being disposed within the bearing surfaces 30 7^d and the other springs are arranged at each end of this central group of four, the end springs being partially disposed in the channels of the bolster columns 7, as clearly shown in Figs. 1 and 4.

35 In the latter figure the position of the springs is indicated by the dotted line. It will be noted that all of the springs are at the same level at their bottom portions, all resting on plate 15 and said springs are also 40 shown as of one height so that their top ends are substantially at one level. A spring cap plate or roller bearing plate 17 is provided having a flat straight undersurface disposed substantially in one plane resting on the top 45 of springs 16, said plate having downwardly projecting portions 17^a at its inner and outer sides extending downward a short distance alongside of the springs for holding the same in position. The plate 17 is substantially 50 rectangular at its central portion but has its ends converging and provided with rectangular projecting portions 17^b which extend into the channels of the columns 7, as shown in Figs. 1 and 4. The plate 17 is provided 55 on its upper surface with a plurality of grooves 17^c forming seats for a plurality of bearing rollers 18. The bolster 19 of the truck has its end projecting between the bolster columns 7 and said bolster is provided 60 on its undersurface with a plurality of roller seats 19^a overlying the seats 17^c and engaging the rollers 18. The bolster at its outer end, has laterally projecting ribs 19^b for limiting the endwise movement thereof. Vertically 65 movable wear plates 20 are provided

which are of channel shape in horizontal cross section, as shown in Figs. 2, 5 and 6, which plates have their channels directed outwardly and embracing the bearing surfaces 7^d of the bolster column 7. The bolster 19 thus 70 has its sides moving in contact with the inner sides of the wear plates 20. The wear plates 20 have downwardly extending projections 20^a disposed centrally thereof at their bottom portions, which projections have a laterally 75 extending lip or hook 20^b. The plate 17 has an aperture 17^d at each end through which the projection 20^a extends, and when the wear plates 20 are in vertical operative position the lip or hook 20^b extends laterally under 80 the plate 17, thus preventing any appreciable lifting of the wear plate 20 relative to the bearing plate 17. The projection 20^a and hook 20^b are inserted through the opening 7^d with the wear plate in inclined position 85 and the plate is then brought to its operative vertical position so that the parts take the position shown in the drawings.

From the above description it is seen that applicant has provided a simple, efficient and compact structure of truck. By having the column of channel shape disposed as shown and described, it is possible to get sufficient room for the number of springs used and at the same time to keep all of the springs at the same level. By having all of the springs at the same level a straight bearing plate 17 can be used. Such a straight bearing plate is much cheaper and more easily made and superior to the offset bearing plate which has heretofore been proposed in connection with the use of six springs, some of which were at a higher elevation than the others. By having a straight bearing plate, a standard A. R. A. bolster can be used without material change, the only revision necessary being the provision of roller seats on the underside of the bolster which is now common practice. The spring bearing plate 15 and end springs, as above described, are conveniently received 100 in the channels of the bolsters. The wear on the columns and bolsters is taken mostly on the wear plate 20 and these plates can be renewed when worn. The present structure affords a simple and efficient manner of holding 105 the plate 20 against vertical movement relatively to the spring plate 17. It will be seen that wear plate 20 rests on top of plate 17 and, as above stated, is held from appreciable vertical movement relatively thereto by the 110 tongue 20^b. With the present structure, a large wearing face for the bolster and bolster column is also provided. All of the parts are constructed and arranged to provide a simple, compact efficient and durable truck.

It will, of course, be understood, that various changes may be made in the form, details, arrangement and proportions of the parts without departing from the scope of applicant's invention, which, generally stated, 120

consists in a device capable of carrying out the objects above set forth, in the novel parts and combinations of parts disclosed and defined in the appended claims.

5 What is claimed is:

1. A truck structure comprising a side frame having in combination, spaced bolster columns, a truck bolster having its end vertically movable between said columns, a spring cap plate also movable between said columns, a vertically movable wear plate between each column and said bolster, said wear plate having a portion extending through said cap plate and underlying a portion of said plate

whereby lifting of said wear plate relatively 15 to said cap plate is prevented.

2. A truck structure comprising a side frame having in combination, spaced bolster columns, a truck bolster having its end vertically movable between said columns, a spring cap plate also movable between said columns, a wear plate disposed between each column and said bolster, said cap plate and wear plate having interengaging means to prevent lifting of said wear plate relatively 25 to said cap plate.

In testimony whereof I affix my signature.

EDWIN W. WEBB.
